UNITED STATES PATENT OFFICE

2,430,073

BAG HOLDER

Leon J. Nowak, Jr., Chicago, Ill.

Application February 5, 1945, Serial No. 576,260

3 Claims. (Cl. 248—99)

1

My invention relates to an improvement in bag holders and has for one purpose to provide an improved method of and means for holding bags on members such as grain spouts, dust spouts and the like.

Another purpose is to provide bag supporting or bag securing means of sufficient strength to hold the bag during the course of filling, and when filled.

Another purpose is to provide bag holding or supporting means which eliminate bag tearing or cutting.

Another purpose is to provide bag securing or holding means which can be quickly and safely employed by a user, without risk of injury to the user.

Another purpose is to provide bag holding means which are quick and efficient in operation.

Other purposes will appear from time to time in the course of the specification and claims.

My invention is illustrated more or less diagrammatically in the accompanying drawings wherein:

Figure 1 is a side elevation;

Figure 2 is a section on the line 2—2 of Figure 1;

Figure 3 is a side elevation on a reduced scale; and

Figure 4 is a diagrammatic illustration of the mode of operation of the bag holder, taken substantially at line 4—4 of Figure 3.

Like parts are indicated by like symbols throughout the specification and drawings.

Referring to the drawings 1 generally indicates the lower generally cylindrical portion of a feed spout having a bottom or bag securing flange 2 and an upper positioning flange 3 extending outwardly from the spout itself. 4 generally indicates a support or base which may be secured to the spout for example by positioning flanges 5 and rivets or other securing means 6. The support 4 is shown as having a lateral extension 7. Mounted on the support are two pairs of flanged rollers or guides 8 which serve to guide and position a longitudinally movable flanged rack bar 9 having the driving rack 10 arranged along one edge and teeth 11 along the other. The rack bar 9 is normally urged against any suitable limiting stop 12 by the action of the coil spring 13 which is anchored at one end, as by the pin 14, 50

2

on the base extension 7 and is secured at the other end, as by the pin 15, to the outer end of the rack bar 9. 15a is any suitable handle whereby the user can manipulate the rack bar. In 5 mesh with the rack 10 is the pinion 16 mounted on a shaft 17 which is supported in any suitable bearing in the support or base 4 including a downwardly extending portion 18. The shaft 17 carries at its lower end a flange or disc 19 with a pair of downwardly extending pins 20, 20a. The dog 21 pivoted as at 22 on the base 4 is normally urged by the spring 23 into engagement with the teeth 11, whereby it is adapted to prevent the spring 13 from moving the rack bar 9 to the right, referring to the position of the parts in Figures 1 and 2. 24 is a handle whereby the operator can move the dog 21 to inoperative position when a return of the rack bar 9 to its initial position is desired. In the particular form of the device 20 herein shown, a cylindrical portion 1 of the spout is recessed as at 30, to form an arcuate concave walled space to receive part of the flange 19 and to permit the center of rotation of the pin carrying flange 19 to be somewhat closer to the center 25 of the spout.

In the use of my device the user threads the empty bag 35 about the spout 1. To insure a proper positioning of the bag he may employ the upper flange 3 as a gauging means, holding 30 the bag with its upper edge at the level of the lower side of the flange 3. At the same time he threads the edge of the bag between the pins 20 and 20a, as shown in Figure 3. He then pulls the rack bar 9 to the left, referring to the position of parts as shown in Figures 1 and 2. The result is a rotation of the gear 16 and thus of the pins 20 and 20a through several revolutions. Since the upper edge of the bag is between the two pins the result is to wind in the slack of the 35 bag and to tension the bag tightly about the exterior of the spout 1. Since this tensioning takes place above the flange 2, that flange forms an effective supporting means for preventing the bag from escaping downwardly. The supporting or locking effect is sufficient to permit the bag to support its own weight and the weight of the charge delivered to its interior through the spout 1. While it is receiving the charge it is kept locked in position by the engagement of the dog 40 21 with the teeth 11. The means for controlling

the flow of the charge through the spout 1 do not form part of the present invention and are not herein described or shown.

After any suitable charge has been delivered to the interior of the bag, and after the delivery of material has terminated, the bag can be released by the operator by so moving the handle 24 as to withdraw the dog 21 from the teeth 11. The action of the spring 13, and the tension of the bag itself are then effective to cause the rack bar 9 to move toward the right and to unreel or release the slack of the bag. Any suitable means not herein shown may therefore be used to close the bag. Or the bag, with its top open, may be dropped on any suitable support or conveyor and be removed elsewhere for further handling or treatment.

It will be understood that whereas I show only one of the twisting mechanisms above described, two or more may be employed, preferably unitarily rotated by or through any suitable driving connection. It will also be understood that the particular driving means illustrated is but one of a number which might be employed. I may for example employ a positive drive for the rack bar 9, controlled in any suitable manner by the operator. I may for example employ a pneumatic or hydraulic system for moving the rack bar in the desired direction. Any suitable return means may also be employed to take the place of the spring 13.

It will be realized that, whereas I have described and illustrated a practical and operative device, nevertheless many changes may be made in the size, shape, number and disposition of parts without departing from the spirit of my invention. I therefore wish my description and drawings to be taken as in a broad sense illustrative or diagrammatic, rather than as limiting me to my precise showing.

For example the shape and nature of the twisting element may be widely varied, and the means for preventing the escape of the tensioned bag top from the spout may be widely varied. I may employ a bell mouthed spout or a spout having a variety of outwardly extending bag gripping elements, or a roughening of the outer surface of the spout. I may employ frictional material on the spout or on the bag or on both.

Where I employ the term "tensioning," in connection with the reduction of the effective circumference of the bag it will be understood that I do not wish the term to be limited specifically to subjecting the bag to positive tensioning about the support. For example, in relation to the structure as shown, the spout 1, or other support to which the bag is secured, has an outwardly extending lower enlargement or flange 2. With reference for example to Figure 1, if the pins 20 and 20a are rotated sufficiently to reduce the effective circumference of the neck of the bag to less than the circumference of the flange 2, than the gravitational pull of the bag, and of the charge in the bag, will be effective to draw the reduced part of the bag downwardly against the flange 2. Thus, even though the bag is not positively tensioned about the exterior of the sleeve 1, downward escape of the bag over the flange 2 will be prevented, and the weight of material in the bag will maintain a tight thrust of the bag against the edge of the flange 2 which is effective to prevent the escape of any substantial amount of dust, or of the charge itself where light or powdered material is being delivered. I intend the language of the claims to be interpreted in con-

nection with this fact. It is not necessary, although it may be desirable, positively to tension the bag around the exterior of the spout or support 1.

5 The use and operation of my invention are as follows:

My invention may be advantageously employed as a bag support or holder for holding a bag in position in relation to a spout through which 10 a charge of material is delivered to the interior of the bag. When so used the loose neck of the bag is tensioned about the exterior of the spout, with the flange 2 preventing the bag from escaping from the bottom of the spout. When the bag is thus locked in position, with the dog 21 holding the rack bar 9 in the locking position, a charge of material is dropped into the bag. The bags used are preferably of material strong enough to support the weight of the charge, and the entire weight of the filled bag is taken by the 15 end of the spout and the flange 2. The filled bag is thus suspended by its upper edge or neck. The bag may be filled over any suitable support, for example the conveyor generally indicated at 20 50 in Figure 3. When the bag is filled, the user can drop it on the conveyor by merely releasing the dog 21 by manipulating the handle 24. When the dog 21 is released the spring 13, and the tension of the bag, are effective to unwind the pins 20, 20a or their equivalent. The bag is then free to drop by gravity upon the conveyor 50, which carries it out of vertical alignment with the spout, for further handling or disposal.

I claim:

35. 1. In a bag holding assembly, a support for the bag having a generally peripherally continuous bag supporting flange adapted to enter the open mouth of and lie in a plane generally perpendicular to the longitudinal axis of the bag, a bag 40 twister having fingers located above the flange, one finger adapted to engage the inside, another the outside of the material of the bag mouth, means for rotating the fingers to twist the material and fold it upon itself to constrict the bag 45 mouth above the flange, the axis of rotation of the twister being located inside the periphery of the flange and so disposed with respect to the flange that after the twist has been made, the twisted portion of the bag below the ends of the 50 fingers lies entirely inside and above the outer periphery of the flange.
2. In a bag holding assembly, a support for the bag having a generally peripherally continuous bag supporting flange adapted to enter the open 55 mouth of and lie in a plane generally perpendicular to the longitudinal axis of the bag, a bag twister having fingers located above the flange, one finger adapted to engage the inside, another the outside of the material of the bag mouth, 60 means for rotating the fingers to twist the material and fold it upon itself to constrict the bag mouth above the flange, the axis of rotation of the twister being located inside the periphery of the flange and so disposed with respect to the flange 65 that after the twist has been made, the twisted portion of the bag below the ends of the fingers lies entirely inside and above the outer periphery of the flange, the fingers being downwardly extending and terminating above the flange at such 70 a distance that the twisted portion of the bag below the finger ends terminates immediately adjacent the upper surface of the flange.

3. A bag holding assembly, including a spout, a bag supporting flange extending radially from 75 and about it, having an upper surface generally

perpendicular to the outer wall of the spout, twisting means having fingers located entirely above the upper surface of the flange, one finger adapted to engage the inside, another the outside of the material of the bag at the mouth, means for rotating the twister to cause the fingers to twist the material and fold it upon itself to constrict the bag mouth upon the spout above the flange, the axis of rotation of the twister being located inside the periphery of the flange and the 10 twisted portion of the bag below the fingers lying entirely inside the outer periphery of the flange.
